H. F. WAITE,
X-RAY APPARATUS,
APPLICATION FILED JAN. 31, 1919.

1,334,936.

Patented Mar. 23, 1920.

Inventor:
Harry F. Waite,
by *Albert G. Davis*
His Attorney.

UNITED STATES PATENT OFFICE.

HARRY F. WAITE, OF NEW YORK, N. Y., ASSIGNOR TO GENERAL ELECTRIC COMPANY,
A CORPORATION OF NEW YORK.

X-RAY APPARATUS.

1,334,936.

Specification of Letters Patent. Patented Mar. 23, 1920.

Application filed January 31, 1919. Serial No. 274,201.

To all whom it may concern:

Be it known that I, HARRY F. WAITE, a citizen of the United States, and a resident of the city of New York, county of Queens, 5 and State of New York, have invented a new and useful Improvement in X-Ray Apparatus, of which the following is a specification.

The object of my invention is to provide a 10 light and portable X-ray apparatus, which may be placed in any desired position and may be used to any desired extent without regard to climatic conditions or disturbances and without danger to any one from high 15 tension feed wires or other high tension parts of the apparatus. A further object is to provide an apparatus in which the X-ray tube is immersed in oil and so are all exposed parts which are energized when the 20 tube is in use so that under no circumstances can there be any leakage of high tension current from one terminal to another, such as sometimes occurs when such devices are placed in air.

25 These and other objects are accomplished by my invention one embodiment of which is shown in the annexed drawing, forming a part hereof, in which the figure is a perspective, fragmentary view, with the electrical connections shown diagrammatically.

30 My improved apparatus consists of a box or casing 1 which is preferably made of metal and is oil tight, so that it will hold transformer oil without leakage. Its top 2 is preferably made of fiber. The casing is 35 lined with metal except at its center where it is provided with metal slides 3 by means of which the opening for the X-rays generated by the tube 4 may be regulated. The 40 casing, preferably has sufficient transformer oil therein to cover the tube 4 an inch deep, as indicated by the line 5 near the top of the casing 1.

The tube 4 is supported by suitable pedestals 6, one at each end, which rise from the 45 bottom 7 of the box 1, and these pedestals carry wires which run to the anode 28 and hot cathode 29 respectively of the tube 4. These wires are also connected to the 50 secondaries 8 and 9 respectively. These secondaries are energized by their primaries 10 and 11. The primaries are connected with an alternating current generator 12, or any other suitable source of power, as fol-

lows: One terminal 13 of this generator has 55 a wire 14 that runs to the primary 10, and this primary also is connected to a wire 15 which runs to a regulating apparatus 16 which is connected to a wire 17 that runs to the terminal 18 of the generator 12. A wire 60 19 connects the wire 14 to one terminal of the primary 11. The other terminal of this primary is connected to a wire 20 which runs to a regulating device 21 which is connected by a wire 22 with the wire 17 so that 65 the primaries may be regulated independently. The secondary 8 has a wire 23 that runs to the anode 28 and another wire 24 which runs to the cathode 29. One terminal of the secondary 9 is connected to the wire 70 24 and the other terminal of the secondary 9 is connected by a wire 25 to the opposite terminal of the cathode 29. The current passing through the hot cathode 29 may be regulated through the controller 21. 75

The regulating apparatus 16 and 21 may be placed either in or on the box 1, or in any other convenient location.

In view of the foregoing, the operation of my improved device will be readily understood. Assuming that an alternating current, of the conventional kind, is generated by the dynamo 12; this current is passed through the regulating devices and wires so as to energize the primaries 10 and 11, the 80 primary 11 being preferably the first to be energized so as to have the hot cathode in a glow before any effort is made to energize the anode 28. When the anode 28 is energized by making the primary 10 active, in 85 the conventional manner, X-rays are generated and passed out of the apparatus through the oil and the fiber cover and the space between the slides 3. All stray rays are intercepted by the metal of the box 1 90 and the metal lining of the cover 2. When 95 X-rays are no longer needed, the apparatus may be shut off and disconnected in the conventional manner.

While I have shown and described, one 100 embodiment of my invention, it is obvious that it is not restricted thereto, but is broad enough to cover all structures that come within the scope of the annexed claims.

What I claim is:

1. In a device of the class described, a 105 box, oil therein, an X-ray tube, a transformer immersed in said oil and means for

connecting the same to said tube so that said tube may generate X-rays while immersed in oil.

2. In a device of the class described, a box, an X-ray tube mounted therein of the hot cathode type, oil in said box surrounding said tube and two transformers in said oil, one adapted to heat the cathode and another to generate X-rays.

10 3. An X-ray apparatus comprising a step-

up transformer, an X-ray tube having terminals, conductors directly connecting the high tension winding of said transformer to the terminals of said tube, a container for said transformer and tube and a body of oil in said container enveloping the said conductors and terminals, and surrounding said transformer and said tube. 15

HARRY F. WAITE.
